TRAY OR SIMILAR ARTICLE

Lottie M. Link, 710 Brook St., Bryn Mawr, Pa.

Filed May 3, 1960, Ser. No. 60,443

Term of patent 14 years

(Cl. D44—10)

Fig. 1.

Fig. 2.

The side opposite that shown in Figure 2 is substantially identical thereto.

I claim:

The ornamental design for a tray or similar article, substantially as shown and described.
